UNITED STATES PATENT OFFICE

1,927,645

WINDMILL CONSTRUCTION

John August Lund, Batavia, Ill., assignor to
Challenge Company, Batavia, Ill., a corporation
of Illinois

Original application January 15, 1930, Serial No.
420,865. Divided and this application March
28, 1932. Serial No. 601,571

1 Claim. (Cl. 184—5)

This invention relates in general to a windmill construction and is particularly concerned with novel means for lubricating its various moving parts. The present invention is a division of my 5 pending application for patent for a "Guide head", filed January 15, 1930, U. S. Serial No. 420,865.

It is an object of this invention to provide improved means whereby the guide head and 10 other moving parts of the windmill will be automatically and efficiently lubricated.

It is a further object of this invention to provide an improved lubricating system for windmills, which is so designed that oil will be carried upwardly along the guide rods for the cross head and distributed to the rollers on the cross head, which are in engagement with the guide rods, thereby assuring that the cross head rollers and guide rods are at all times provided with a 20 sufficient quantity of lubricant.

It is also an object of this invention to provide in a windmill construction, improved means for lubrication of the pitman connection to the cross head.

25 The invention comprises the novel structure and combination of parts hereinafter described and more particularly pointed out and defined in the appended claim.

30 In the accompanying drawing, which illustrates a preferred embodiment of this invention and in which similar reference numerals refer to similar features in the different views:

Figure 1 is an enlarged plan view of a windmill cross head with which my present invention is adapted to be used.

Figure 2 is a plan view of the cross head showing its connection to the driving mechanism of my windmill construction, and means for collecting and distributing the lubricant to the various 40 moving parts associated with the cross head.

Figure 3 is a fragmental elevational view partly in cross-section showing the details of the lubricating system for the cross head, taken substantially on line III—III of Figure 2.

45 Figure 4 is a fragmental end elevational view of the guiding mechanism and lubricating means.

As illustrative of this invention, there is shown a casing 10 for housing the mechanism for driving the pump rod. In this instance, a standard 50 or web 11, Figure 3, is provided in the casing. The upper surface of the standard 11 is provided with an upstanding flange 12 which forms a trough or basin for receiving a lubricant. The standard 55 is bored to define a vertical passageway 13 therethrough to receive a pump rod 14 which is

mounted for reciprocable movement. The upper portion of this passageway is provided with an upwardly extending hub or collar 15 for preventing leakage of the lubricant from the basin into the pump rod bore. A pair of spaced guide rods 60 66 60 and 17 are arranged on each side of the pump rod and are threadedly secured within the lubricant basin to the standard 11. The guide rods are maintained in parallel spaced relationship by means of a cross piece 18 which extends between the upper ends thereof. This cross piece may be secured to the guide rods in any well-known manner.

A cross head 19 is threadedly secured at its 70 lower extremity to the pump rod, and comprises 75 guide rollers 20 and 21 which are journalled respectively upon the shafts 22 and 23 which extend through and are supported by the body portion of the cross head 19. Each guide roller is 80 provided with a peripheral groove 24 which is 85 formed to receive a vertical guide rod therein. It is to be noted that the axis of rotation of each roller as thus mounted is at right angles to the plane established by the guide rods, and also the 90 guide rollers are arranged on the outside of the guide rods. With this construction, both rollers may roll against their respective guide rods. Consequently, if the cross head should twist, the rollers would still be capable of rolling and no objectionable abrasive action upon the guide rods 95 90 would occur because there would always be a rolling action between both rollers and their respective guide rods. Further, as arranged, the thrust of the pitman in operation will be directed in the plane of the guide rods so as to avoid twisting the cross head.

A shaft 25, which extends parallel to the axis of rotation of each guide roller, is journalled midway between the guide rollers in bearings 26 95 and 27 which are integrally formed with the body portion of the cross head 19. Reciprocable movement is imparted to the pump rod by means of gears 28 which are rotatably mounted upon the standard 11 so as to run in oil and operate in a plane on each side of the guide rods in spaced relation thereto. The gears 28 form crank members to which one end of each pitman 29 is connected. The other ends of the pitman are respectively connected to the ends of the shaft 25 105 which, it will be noted, extends parallel with the rollers so that the thrust of the pitman will be directed substantially in a plane passing through the guide rods, thuswise avoiding any tendency to twist the cross head. The gears 28 are driven 110 by a pair of pinions 30 in mesh therewith, said

pinions being connected to a driving shaft 31 which is journalled in any approved manner in the casing 10. The shaft 31 carries at one end a wind-wheel, not shown in the drawing, of well-known construction.

The lubricating means for oiling the moving parts of the windmill construction includes a spiral member 32 of wire or the like which surrounds each guide rod. The upper end of each member 32 is loosely connected to the cross head 19 in such a manner that the coil of wire will be suspended below the guide head and will be moved along the guide rod as the pump rod reciprocates. When the pump rod has reached its lowest point of travel, the spiral coil of wire will dip into the lubricant in the lubricant basin, and, with the upward movement of the pump rod, the coiled wire will act as a conveyor to distribute the oil contained thereon along the guide rod. Each of the guide rollers is provided with a radial aperture 33 which extends from the groove 24 to the axis thereof. It is, therefore, evident that, during the reciprocable motion of the pump rod, a portion of the lubricant which has been distributed along the guide rod will pass through the aperture 33 to lubricate the axles of the guide roller. In order to lubricate the bearing surface of the shaft 25 which is within the bearings 26 and 27 as well as the portion which extends through the end of each pitman, a metal plate 34 of slightly concave formation is provided with spaced apertures through which the guide rods extend. An oil passage 35 is provided in the plate directly above the shaft 25.

The plate 34 will, therefore, be carried by the cross head during the reciprocable movement thereof, and the walls of the apertures through which the guide rods pass will skim or pick up a portion of the lubricant which has been distributed therealong. The lubricant which has thus been gathered will flow along the plate towards the oil passage 35 and pass therethrough to the shaft 25 to lubricate the same.

This invention, therefore, provides an improved windmill construction having novel means for automatically oiling the cross head rollers, guide rods and pitman connection to the cross head, whereby a sufficient amount of oil is at all times supplied to these parts.

I am aware that many changes may be made and numerous details of construction may be varied through a wide range without departing from the principles of this invention, and I therefore do not purpose limiting the patent granted hereon otherwise than necessitated by the prior art.

I claim as my invention:

In a windmill construction, a pair of spaced guide rods, means for lubricating said guide rods, a cross head in rolling engagement with said guide rods, a rotatable shaft carried by the cross head, and means for lubricating the shaft comprising a dished plate resting upon said rollers and in wiping engagement with said guide rods, said plate having an aperture above the shaft.

JOHN AUGUST LUND.
